UNITED STATES PATENT OFFICE.

WILLIAM H. DOUGLAS, OF BELLEVILLE, NEW JERSEY, ASSIGNOR TO HEALEY & CO.,
OF NEW YORK, N. Y.

DESIGN FOR A WIND-SHIELD.

43,798.

Specification for Design.

Patented Apr. 1, 1913.

Application filed January 18, 1913. Serial No. 742,956. Term of patent 7 years.

To all whom it may concern:

Be it known that I, WILLIAM H. DOUGLAS, a citizen of the United States, residing in Belleville, in the county of Essex and State of New Jersey, have invented a new, original, and ornamental Design for a Wind-Shield, of which the following is a specification, reference being had to the accompanying drawing, forming part thereof.

The figure is a front elevation of a wind shield showing my design.

I claim:

The ornamental design for a wind shield as shown.

WILLIAM H. DOUGLAS.

Witnesses:

THEO. G. HOSTER,
PHILIP D. ROLLHAUS.
